G. H. WHEARY
DRAWER CONSTRUCTION

Filed Aug. 4, 1923

UNITED STATES PATENT OFFICE.

GEORGE HENRY WHEARY, OF RACINE, WISCONSIN, ASSIGNOR TO WHEARY BURGE TRUNK COMPANY, OF RACINE, WISCONSIN, A CORPORATION OF WISCONSIN.

DRAWER CONSTRUCTION.

Application filed August 4, 1923. Serial No. 655,701.

To all whom it may concern:

Be it known that I, GEORGE HENRY WHEARY, a citizen of the United States, and resident of Racine, in the county of Racine and State of Wisconsin, have invented new and useful Improvements in Drawer Construction, of which the following is a description, reference being had to the accompanying drawings, which are a part of this specification.

This invention relates to certain new and useful improvements in drawer constructions, and refers more particularly to a convertible drawer for trunks of the wardrobe type.

In wardrobe and other trunks it is desirable to provide a compartment of ample size adapted to carry one or more ladies' hats, which compartment, when not in use for hats, may be employed in the ordinary manner as drawers for other articles. In Letters Patent No. 1,125,421, issued January 19, 1915, and No. 1,139,317, issued May 11, 1915, drawer constructions are illustrated for accomplishing this purpose.

These structures, however, are cumbersome, expensive to manufacture and lack that simplicity necessary for a commercially successful wardrobe trunk and, therefore, it is an object of my invention to provide a drawer construction wherein the same may be either used as an ordinary drawer or inverted to provide, with the drawer therebeneath, a hat compartment.

This invention has for another object to provide a drawer having its front face in the form of a hinged door adapted to be readily releasably secured in closed position.

A further object of this invention is to provide a drawer of the character described having means for preventing the spreading of the walls when the door is in closed position whereby the drawer has the strength of the ordinary drawer.

It is a further object of this invention to provide a drawer of the character described having the forward edges of its side and bottom walls faced with a metallic band or strip to which a front portion is hingedly connected, the front portion having means providing a rigid connection with the bottom and side walls when the drawer is

closed to form a durable and rigid drawer.

And a still further object of this invention resides in the provision of a drawer construction of the character described in which the movable front face or door thereof is provided with a spring lock engageable with the adjacent side wall of the drawer proper when closed to readily releasably secure the door closed, the lock preferably having means to prevent springing or spreading of the side walls and the consequent disengagement of the lock.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a fragmentary, perspective view of the lower portion of the drawer and wardrobe sections of a wardrobe trunk equipped with a convertible drawer embodying my invention;

Figure 2 is a view similar to Figure 1 illustrating the convertible drawer with its front face or door partly opened and the drawer therebeneath in partly opened position, and

Figure 3 is an enlarged, fragmentary, sectional view taken through Figure 1 on the plane of line 3—3.

Referring now more particularly to the accompanying drawings, in which like numerals designate like parts throughout the several views; 5 designates the wardrobe section of a trunk and 11 the drawer section, in which a plurality of drawers 12 are independently slidably mounted and adapted to be locked against unauthorized removal, by a locking bar 13.

One of the drawers 12 is preferably provided with special fittings, not shown, to

adapt the same for use as a lady's hat compartment or any other special use. When so employed it is generally necessary that additional space be provided and the drawer 12', thereabove, is inverted as illustrated in the drawings.

Each drawer has its front wall or face 14 secured in place by an angle band or strip member 15 which is preferably constructed 10 as illustrated in Figure 3 with a lateral extension or flange 16 at its apex to provide a stop engageable with the forward edge 17 of the trunk-side walls to limit the inward sliding movement of the drawer.

15. The front wall 14' of the drawer 12', in lieu of being rigidly secured to the band or strip member 15, has one end hingedly connected with the strip member, as at 18, permitting its free swinging to and from closed 20 position to facilitate the opening of the drawer 12 containing the hats or other special articles. A spring lock 19 comprising a front plate 20 having a part 21 extended beyond the end and then directed 25 inwardly, as at 22, to engage in a slot or opening 23 in the strip member 15 when the drawer is closed and a bolt housing 24 in which a bolt 25 is slidably mounted is carried by the door 14' at its free end.

30. Bolt 25 is normally yieldably urged outwardly by a spring 26, and the outer end 27 thereof is tapered to permit the movement thereof against its spring when the front 14' is closed, the bolt engaging behind the 35 front face portion of the strip 15, as best illustrated in Figure 3. To unlock the door or front face of the drawer 12', the bolt 25 is provided with a pin or lug 28 which projects beyond the face of the plate 20 through 40 a slot or opening 29 therein.

As will be readily obvious, the projections 21 and 22 not only provide a cover for the bolt 25, but limit the inward or closing movement of the door and prevent spreading of the drawer side walls. To further limit closing movement and prevent crushing in of the front wall 14, one or more lug members 30 are secured to the front adjacent its lowermost edges, when the drawer 50 is in normal position, and overlie the front face of the strip 15. The lugs 30 have their outer-most ends directed inwardly, as at 31, to form projections adapted to engage in slots 32 in the strip 15 to thus prevent spreading of the bottom wall of the drawer, 55 as will be readily obvious.

When not in use to form part of a hat or other special compartment, drawer 12' is inverted from the position illustrated in the 60 drawings and may then be used as an ordinary drawer. The construction illustrated insures the strength and rigidity of an ordinary drawer having a fixed front, and when it is desired to use the drawer for a special 65 purpose, wherein it is desirable to remove

the contents without sliding the drawer outwardly, the front may be opened as will be readily obvious.

From the foregoing description taken in connection with the accompanying drawings, 70 it will be readily apparent that I provide a drawer of the character described which will not in any manner mar the general attractiveness of the trunk, which will be strong and durable, and which may be used 75 as an ordinary drawer, as a special compartment or inverted and employed in conjunction with the adjacent drawer to form a large compartment for the reception of 80 hats or any other articles.

What I claim as my invention is:

1. In a device of the character described, a drawer having its front open, a hinged door normally closing the front of the drawer, a lock carried by the door and engageable with the adjacent drawer wall when closed to releasably secure the door closed, and a part carried by the lock and engageable in a drawer recess to prevent spreading of the drawer walls when the door is closed.

2. In a device of the character described, a drawer, comprising bottom, rear and end walls, an inwardly extending strip member carried by the front edges of the drawer walls, a door forming a drawer front wall, means hingedly connecting one end of the door with the strip member adjacent one side wall, and locking means carried by the other end of the door and engageable with the strip member adjacent the other side wall to releasably secure the door in closed position.

3. In a device of the character described, a drawer, comprising bottom, rear and end walls, an inwardly extending strip member carried by the front edges of the drawer walls, a door forming a drawer front wall, means hingedly connecting the door with the strip member, locking means carried by the door and including a spring urged locking bolt adapted to engage behind the strip member to releasably secure the door in closed position, and a projection carried by the locking means and engageable in a recess in the strip member to prevent spreading of the adjacent drawer wall.

4. In a device of the character described, a drawer, comprising bottom, rear and end walls, a door providing a front wall therefor, means connecting one end of the door with one end wall, the other end wall and the bottom wall having locking recesses therein, means carried by the door and engageable in said locking recesses when the door is closed to prevent spreading of the drawer walls, and means operable to lock the door in closed position.

5. In a device of the character described, a drawer, comprising bottom, rear and end

walls, an inwardly extending strip member carried by the front edges of the drawer end and bottom walls, a door forming a drawer front wall, means hingedly connecting one end of the door with the strip member at one end wall, locking means carried by the door adjacent its other end and engageable with the strip member at the other drawer end wall to releasably secure the

drawer in closed position, and a laterally and inwardly extended projection carried by the door adjacent its lower edge and engageable in a recess in the strip member at the bottom wall to prevent spreading of the bottom wall when the door is secured in closed position.

In testimony whereof I affix my signature.
GEORGE HENRY WHEARY.
